UNITED STATES PATENT OFFICE.

CHARLES WILLIAM SHIPPEE, OF MILFORD, MASSACHUSETTS.

MACHINE FOR MANUFACTURING CONGRESS BOOTS.

SPECIFICATION forming part of Letters Patent No. 390,263, dated October 2, 1888.

Application filed February 20, 1888. Serial No. 264,629. (No model.)

To all whom it may concern:

Be it known that I, CHARLES WILLIAM SHIPPEE, a citizen of the United States, residing at Milford, in the county of Worcester and State of Massachusetts, have invented certain new and useful Improvements in Mechanism for Facilitating the Manufacture of Congress Boots; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

On the 12th day of September, 1887, I filed in the Patent Office application No. 249,444, for a patent for improvement in mechanism for folding the edges of the gored opening and also the top edge of the lining of a Congress boot, and in auxiliary mechanism for facilitating the application and fixing to said lining of the elastic gores and the portions of the top of the boot which are also to be secured to said elastic gores.

This application is for a separate patent for that part of the mechanism of said application No. 249,444, which is described therein as the "auxiliary mechanism," &c. Therefore the invention comprised in this application consists in a mechanism for facilitating the application and fixing to the lining of a Congress boot, after the edges of the gored opening and also the top edge of said lining have been folded and pressed, of the elastic gores and the portions of the top of the boot which are to be secured to the said elastic gores, and also to the said lining, all as shown and as herein-after described.

In the drawings, Figure 1 is a top view of a portion of a bench or table having gages and their operative mechanism applied thereto, to be hereinafter described. Fig. 2 is a transverse section of said bench or table. Fig. 3 is a front view of said table with its gages and operative mechanism. Fig. 4 is a similar view to Fig. 1, but showing some of the parts in a different position from that shown in Fig. 1, as will be hereinafter described. Fig. 5 is a view of one half of a lining of a Congress boot, the edges of the gored opening and the top edge of the lining being folded, as shown.

In carrying out my invention, I secure on a long bench or table a series of gages arranged in sets, each set being to facilitate the application and fixing to a pair of linings which have the edges of the gored opening therein and their top edges folded, as shown in Fig. 5, of the elastic gores and the pieces of leather or material which are to be secured to said gores and linings. The drawings illustrate but one set of said gages.

The linings before being applied to the gages are to be arranged in pairs or rights and lefts and sewed or connected together down their front edges from the top to or about to the point where the vamp will be sewed to the top or ankle portion of the boot.

A denotes the table, to which is secured a metallic plate, a^2 , against the under side of which and in an opening in the table I place a heater to be warmed by steam or otherwise, and upon the upper surface of said plate are placed two plates, K L, provided with inclined slots g^2 . Screws h^2 pass down through said slots into the plate a^2 , and serve as guides to said plates in their movements. Secured to each of the plates K L are two gages, M N, the lower ones, M, being fixed to said plates K L, and the upper ones, N, pivoted thereto, as shown, so that they can be turned up into the position shown in dotted lines in Fig. 2. Each of the gages N is provided with a hook which receives a bail, k^2 , extending down through slots m^2 in the table and having its ends connected to a weight, l' , (see Figs. 2 and 3,) said weight and bail serving to hold the gage N when turned up into a vertical position, and to give pressure to it when turned down upon an elastic gore, as shown in Fig. 4.

Pivoted to the plates K L are two connecting-rods, O P, which are jointed to a lever, Q, pivoted to the table at n^2 . The table is provided with a slot, R, in its front edge, as shown, and has a line, S, marked thereon, said line to serve as a guide in applying a pair of linings to the table, as seen in Figs. 1 and 4. The top of the leg portion thereof being laid against such line, as shown, that portion of the linings to the right of the line 2 2. Fig. 5 is introduced into and hangs down through the slot R in the table and the portion to the left of the line 2 2 in said figure lies upon the top of the table, the folded edges of the openings in

said linings being made to touch the edges of the gages M, all as shown in Fig. 1 in full lines, and in dotted lines in Fig. 4. Owing to the construction and arrangement of these gages they 5 will answer for several sizes—say from 5 to 11—the numbers indicating the sizes being marked on the gages M, as shown. The drawings represent the linings to be size 5, and before adjusting said linings on the table to the gage 10 said gage is to be moved by means of the lever Q, so that the line indicating size 5 will coincide with the line S on the table. Then the linings are to be adjusted to the gages and 15 weights placed thereon to hold them in position. While the aforesaid adjustment is being done the gages N are standing in a vertical position, as shown in dotted lines in Fig. 2. Cement is next to be applied to the under, and then to the upper, surfaces of the folds a 20 b c d e. Then the elastic gores are laid over and upon the folds b c d. Next, the gages N are turned down upon the gores and the pressure thereon, caused by the weights l', will press the gores into contact with the folded 25 edges of the openings in the linings and cause them to adhere firmly thereto. Next, the front or instep and leg portion T of the boot top which goes between the elastic gores on the front is to be cemented on its inner surface 30 next its side edges and top edge and applied to the said gores, with its side edges, y, resting against the inner edges, z, of the gages N. As shown in Fig. 4, a strap, X, is inserted between the top edge of the portion T and that 35 of the linings, and pressure is then applied to said cemented portions by means of one or more weights. The back portions, U, of the boot-top are next to be applied in the same manner by cement to the gore and the top 40 edge of the linings, the inclined edge a² of the portions U being laid against the inclined edge b² of the gages N, as shown, pressure being applied to the cemented portions by 45 weights until the cement has set, after which the gages N are to be raised to a vertical position, the weights removed, and the linings, with the portions of the boot-top applied thereto, removed from the table, and another set of linings substituted therefor.

50 The set of linings removed from the gages are to have the parts of the boot-top which have been cemented thereto further connected together at the edges by one row of stitching only of a sewing-machine.

55 The cement employed in connecting the edges of the parts, as described, assists materially in holding them together, and it is necessary to use but one row of stitches to complete the union, thus effecting a saving over the old method 60 of using two rows of stitches, one row being far preferable, particularly in connecting the

sides of the gored opening to the sides of the elastic gore, as with one row of stitches there is much less liability of cutting off the elastic strands of the fabric of which the gore is composed with the needle of the machine than there is when there are two rows, thus overcoming in a great degree the tendency to do injury to the elastic gore during the process of manufacture. The parts are also kept in place to better advantage by being cemented together while being operated upon by a sewing-machine.

A spring, V, provided with a series of holes, d², is secured to the table and bears against 75 the under side of the lever Q, said lever having a stud, c², to enter either of said holes when moved into contact therewith. This device serves to lock the gages when set to any desired size. By pressing down the free end 80 of the spring the stud can be disconnected from either of said holes. Each hole may be numbered, as shown, to indicate the size at which the gage M is set when the stud c² is in either of the holes d² of the spring V.

Having described my invention, what I claim is—

1. The combination of the table A, having thereon the line S, and provided with slots m² and R, the plate a², secured to its top, and a 90 heater, C', resting against said plate and arranged in an opening in said bench, the plates K L, having inclined slots to receive screws or studs secured to the plate a², the gages M, fastened to the said plates K L, and the gages N, pivoted thereto and provided with hooks i², the bails k², weights l', the connecting-rods O P, lever Q, pivoted to the bench and provided with the stud c², spring V, secured to the table and having the series of gage-holes 95 d², all being arranged and to operate substantially as set forth.

2. The combination of the table A, having thereon the line S, and provided with slots m² and R, and having secured to it the plate a², 100 and the heater C', provided with inlet and outlet pipes and arranged against said plate, as shown, the plates K L, having inclined guide-slots g², to receive screws or studs h², secured to the plate a², the gages M, graduated and numbered, as shown, to indicate with the line S the different sizes and fixed to the plates K L, the gages N, pivoted thereto and having hooks i², the bails k², weights l', connecting-rods O P, and lever Q, all being arranged and 115 to operate essentially as set forth.

In testimony whereof I affix my signature in presence of two witnesses.

CHARLES WILLIAM SHIPPEE.
